UNITED STATES PATENT OFFICE.

JOSEPH R. HEBERT, OF BROOKLYN, NEW YORK, ASSIGNOR TO ELIAS A. WILKINSON, OF NEWARK, NEW JERSEY.

SEWING-MACHINE SHUTTLE.

SPECIFICATION forming part of Letters Patent No. 268,229, dated November 28, 1882.

Application filed May 13, 1882. (No model.)

To all whom it may concern:

Be it known that I, JOSEPH R. HEBERT, of Brooklyn, New York, have invented a new and useful Improvement in Shuttles for Sewing-Machines, described in this specification and the drawings thereof.

The invention consists in improvements relating to the shell and tension-spring.

In the form of construction shown, Figure 1 is a top view of the invention. Fig. 2 is a view, partly side and partly in section. Fig. 3 is a perspective view of the tension-spring. Fig. 4 is an end view of the improvement.

In the form of construction shown the tension-spring A is secured to the open-ended shell B by a downward projection, a, on the tension-spring entering a slot, b, in the front end of the shuttle, and a screw, c, having a conical point, screwed into a hole, t, in the side 20 of the shuttle and entering a hole, u, in the projection a on the tension-spring. The tension-spring has a free thread-guide, d, bent down at the point v to hook over the end of the shuttle or in a recess, e, therein, and also 25 has the end x of the body f of the tension-spring bent down to hook into a hole, g, in the shuttle, and a thread-tongue, h, bent down into a depression, s, in the shuttle, and a thread-bend, n, in its shank, forming an opening between the spring and the shell to receive the thread. The shuttle is adapted to receive a bobbin containing thread through its open 30 end B. It is threaded by passing the thread from the bobbin as it is being placed in the 35 shuttle out through the oblique thread-slot m and under the tension-spring A at its thread-bend n. The thread will then be drawn back over the thread-tongue h and under the thread-guide d. The tension of the spring on the 40 thread is regulated by the screw c, the conical point of which, when the screw is turned in the countersink t, will sufficiently change the position of the spring for the purpose. The thread-slot m also serves to show when the 45 thread is about used up on the bobbin. The thread-hole o is for the purpose of receiving the thread sometimes when unusual tension is required.

The details of construction may be varied 50 within the scope of my improvement. For example, the thread-hole o may be dispensed

with, the thread-slot varied, and the tension-spring be otherwise held to the shell.

I claim as my invention—

1. The combination of shell B, having slot b, recess e, hole g, depression s, thread-slot m, and countersink t, with the tension-spring A, having body f, projection a, hole u, thread-guide d, point v, end x, thread-tongue h, and thread-bend n, and the set-screw c, having 55 conical point, substantially as set forth.

2. The combination of shell B, having slot b, hole g, depression s, thread-slot m, and countersink t, with the tension-spring A, having body f, projection a, hole u, thread-guide d, 60 point v, end x, thread-tongue h, and set-screw c, having conical point, substantially as set forth.

3. The combination of shell B, having slot b, thread-slot m, and hole t, with the tension-spring A, having body f, projection a, hole u, 70 thread-guide d, and thread-tongue h, and set-screw c, having a conical point, substantially as set forth.

4. The combination of a shuttle-shell having 75 an open end and an oblique thread-slot with a tension-spring having a body, a thread-guide, and a thread-tongue, the thread-tongue projecting toward the shell, the body having a thread-bend in its shank, and the body and 80 thread-guide separated at their projecting ends, and a set-screw to hold the spring to the shell and regulate the tension, substantially as set forth.

5. The combination, with an open-ended 85 shuttle-shell having a thread-slot, of a tension-spring having a body and a thread-guide separated at their projecting ends, and a thread-tongue projecting toward the shell, and a thread-opening between the shank of the spring 90 and the shell, and a single device for securing the spring to the shell and for regulating the tension, substantially as set forth.

In testimony whereof I hereunto subscribe my signature and affix my seal, in the presence 95 of two attesting witnesses, on the 21st day of April, 1882.

JOSEPH R. HEBERT. [L. S.]
